CLAIM

The ornamental design for a combined storage box and sewing machine, as shown and described.

DESCRIPTION

FIG. 1 is a right side and top perspective view of the sewing table showing my new design;

FIG. 2 is a top, rear and left side perspective view thereof;

FIG. 3 is a front perspective view of the combined storage box and sewing table for sewing machine showing my new design;

FIG. 4 is a top plan view thereof;

FIG. 5 is a front elevational view thereof;

FIG. 6 is a rear elevational view thereof;

FIG. 7 is a left side elevational view thereof;

FIG. 8 is a right side elevational view thereof; and,

FIG. 9 is a bottom plan view.

The broken line showing of environment in FIGS. 1 and 2 is for illustrative purposes only and forms no part of the claimed design.

The bottom of the sewing table is plain and unornamented.
